CLAIM

The ornamental design for a power pack, as shown and described.

DESCRIPTION

FIG. 1 is a front view of a power pack showing my new design;

FIG. 2 is a right hand side view thereof;

FIG. 3 is a rear view thereof;

FIG. 4 is a top view thereof;

FIG. 5 is a bottom view thereof;

FIG. 6 is a left hand side view thereof.

FIG. 7 is a perspective view showing the lead against the main body; and,

FIG. 8 is a perspective view show the lead free for use.

The broken lines showing the connector at the end of the lead are included for the purpose of illustrating a portion of the power pack that forms no part of the claimed design.
